US00D567252S

(12) **United States Design Patent** (10) **Patent No.:** **US D567,252 S**
(45) **Date of Patent:** **** Apr. 22, 2008**

(54) **COMPUTER MONITOR WITH USER INTERFACE**

(75) Inventors: **Jong-Hoon Choe**, Seoul (KR);
Young-Jae Ryu, Seoul (KR);
Woo-Yong Chang, Seoul (KR)

(73) Assignee: **Samsung Electronics Co., Ltd.**,
Kyunggi-do (KR)

(**) Term: **14 Years**

(21) Appl. No.: **29/267,800**

(22) Filed: **Oct. 20, 2006**

(51) **LOC (8) Cl.** **14-04**

(52) **U.S. Cl.** **D14/486**

(58) **Field of Classification Search** D14/485-495;

(57) **CLAIM**

The ornamental design for a computer monitor with user interface, as shown and described.

DESCRIPTION

The file of this patent contains at least one drawing executed in color. Copies of this patent with color drawings will be provided by the Office upon request and payment of the necessary fee.

FIG. 1 is a top front perspective view of a computer monitor with user interface showing our new design;

FIG. 2 is a front elevational view thereof; and,

FIG. 3 is an enlargement of the image area shown in FIG. 2.
